COMBINED BOOKHOLDER AND LAMP

Edwin Lofgren, North Plainfield, N. J.

Application May 11, 1950, Serial No. 9,872

Term of patent 7 years

(Cl. D48—20)

To all whom it may concern:

Be it known that I, Edwin Lofgren, a citizen of the United States of America, and a resident of North Plainfield, in the county of Union, State of New Jersey, have invented a new, original, and ornamental Design for a Combined Book Holder and Lamp, of which the following is a specification, reference being had to the accompanying drawing, forming a part thereof, in which:

Fig. 1 is a top view of a combined book holder and lamp showing my new design;

Fig. 2 is a front elevational view thereof;

Fig. 3 is a rear elevational view thereof; and

Fig. 4 is a side elevational view thereof, the other side being the same.

I claim:

The ornamental design for a combined book holder and lamp, as shown and described.

EDWIN LOFGREN.
